US0D1037972S

(12) **United States Design Patent** (10) Patent No.: **US D1,037,972 S**
(45) Date of Patent: ** Aug. 6, 2024

(54) **STROLLER WHEEL**

- (71) Applicant: **Wonderland Switzerland AG**,
Steinhausen (CH)
- (72) Inventors: **Martijn Hans Van Gelderen**,
Zuid-Holland (NL); **Thomas Stokhof**
de Jong, Zuid-Holland (NL)
- (73) Assignee: **Wonderland Switzerland AG**,
Steinhausen (CH)
- (**) Term: **15 Years**
- (21) Appl. No.: **35/517,836**
- (22) Filed: **Jul. 19, 2022**

(80) **Hague Agreement Data**

- Int. Filing Date: **Jul. 19, 2022**
Int. Reg. No.: **DM/222425**
Int. Reg. Date: **Jul. 19, 2022**
Int. Reg. Pub. Date: **Jul. 21, 2023**

(30) **Foreign Application Priority Data**
